FEEDING MECHANISM

Original Filed Feb. 1, 1930

INVENTOR:
ROBERT C. DANLY,
BY

Robert C. Danly
ATTORNEY.

UNITED STATES PATENT OFFICE

ROBERT C. DANLY, OF CHICAGO, ILLINOIS, ASSIGNOR TO DANLY MACHINE SPECIALTIES, INC., OF CHICAGO, ILLINOIS, A CORPORATION OF ILLINOIS

FEEDING MECHANISM

Application filed February 1, 1930, Serial No. 425,174. Renewed August 28, 1931.

This invention relates to means for serially feeding unfinished cylindrical bushings or the like into the grinding throat of centerless grinding machines, and has for its object:

5 To provide a sectional formation of an inclined runway or track in which the upper face of the runway is formed with a guiding channel, of an angular form in cross section, and down which channel the articles glide and are fed into and finished in the grinding 10 throat or zone of a centerless grinding machine in serial order. The sections of the runway having relative adjustment one to the other in order to afford a guiding channel of a size corresponding with the diameter of a plurality of similar articles, and so that individual articles of a greater diameter or irregular form are rejected and either discharged back into the associated holding 15 20 hopper or over the side of the mechanism.

To provide in connection with the above mentioned inclined runway or track, means for aiding the downward travel of the articles in the guiding channel thereof, with an avoidance of local binding on the part of one or more of the articles during their downward movement.

25 To provide means whereby accidental buckling of the plurality of articles in their downward movement in said runway, is prevented, all as will hereinafter more fully appear.

In the accompanying drawings:

30 Fig. 1 is a side elevation with parts in section, of a feeding mechanism, illustrating the general arrangement of parts in the preferred form of this invention.

Fig. 2 is a detail section on line 2—2 Fig. 1.

35 Fig. 3 is a similar view on line 3—3 Fig. 1.

Fig. 4 is a similar view on line 4—4 Fig. 1.

40 Like reference numerals indicate like parts in the different views.

45 The arrangement of parts in the present feeding mechanism for centerless grinding

machines, shown in Fig. 1, is intended for successively feeding pieces of unfinished work into a curved spout or conductor 1, that is fixedly attached to the frame of said grinding machine and adapted to deliver such succeeding pieces of work into the grinding throat or zone formed by the associated grinding and feeding wheels of the centerless grinding machine.

In the arrangement shown, a holding hopper 3 for the unfinished work to be operated on, is mounted on a portable supporting base 4 that is adapted for rigid yet detachable connection to the frame of a centerless grinding machine with a view to attain proper operative relation during continued use. The hopper 3 is provided with an oscillatory selector plate or slide 5 adapted to serially lift pieces of work from the hopper and discharge the same into the hereinafter described inclined runway or track 6, which is fixedly attached on the base 4 in lateral receiving relation to said selector slide 5 when the same is at the end of its up or lift stroke.

Oscillatory motion of the selector slide 5 is attained by a wiper or crank arm 7 on the end of a shaft 7' which receives constant rotation from a motor which may be located on or in the base 4, in manner substantially similar to the feeder plate or slide of the prior Danly Patent No. 1,725,444, dated August 20, 1929.

In the present construction, the inclined track or runway 6 consists of a main fixed section 6 and an adjustable section 6' arranged in parallel contact, and with the main section 6 formed with an inclined upper face adapted to provide a bearing for the corresponding inclined face of the adjustable track section 6', so that an upward or a downward adjustment of said track section 6 may be attained and a proper size of guiding channel provided to properly accommodate and support particular sizes of the batches of unfinished work to be manipulated. By such

means proper and accurate delivery of pieces of unfinished work into the aforesaid spout or conductor 1 is readily attained in a change of the runway from one to another diameter of the batches of unfinished work the mechanisms must handle in continued actual use.

The vertical face of the fixed track section 6 forms an extension of the adjacent side wall of the hopper 3, and provides bearing 10 contact for the aforesaid oscillatory selector plate 5, the upper face or edge of which has an inclined or bevel formation corresponding with the like formation of the upper face of said fixed track section 6. With such formation 15 of the parts, as the selector plate 5 reaches the end of its up or lift stroke, its inclined upper end will be in line with the inclined upper face of the fixed track section 6, and a piece of unfinished work held in lifting engagement with the upper face of the selector plate 5 by the vertical wall of said track section will slide by gravity into the receiving channel or trough of the inclined runway or track aforesaid.

25 In the construction shown, the work receiving channel or trough of the inclined runway or track, is formed by the inclined upper face of the fixed track section 6 and a corresponding reversely inclined formation of the adjustable track section 6' as shown.

Arranged vertically above the channel or trough of the runway above described, and extending in parallel relation thereto, a rider rail 8 is fixedly supported with its under face 30 in adjacent relation to the tops of the passing pieces of work to prevent accidental buckling action between adjacent pieces of work and a consequent lateral escape of said pieces from the runway.

40 Another part of the invention involves an endless belt 9, preferably of a closely wound spiral formation, supported at its respective ends by sheaves 10 journaled on the aforesaid adjustable track section 6' and the arrangement 45 is such that one stretch of the endless belt extends along the bottom of the conducting channel of the track and is adapted to have conducting contact with the under surfaces of pieces of work, of the smaller diameters, to aid in their downward travel. In 50 said construction the driving sheave 10 of the endless belt 9 receives rotation from a power shaft through an intermediate connection 11 of the universal and extension type, so that 55 regardless of the adjustment of the track section 6' rotation of the driving shaft 10 is efficiently maintained.

In adjacent relation to the mid-length of the runway or track 6, 6', a revolute disk 12 carrying a plurality of radial blades 12' is mounted on the main base, with such blades adapted to engage the pieces of work on the runway, to regulate and retard the passage of such pieces of work along the upper portion of said runway, as described in detail in

another application for patent, Serial No. 425,174, filed February 1, 1930, and constant rotation of the revolute disk 12 is attained by connection thereof with an adjacent power source.

Having thus fully described my invention, what I claim as new, is:—

1. In a feeding mechanism of the type described, the combination of a work holding hopper and its vertically moving selector slide, of an inclined runway, comprising a fixed longitudinal section formed with an inclined upper face and a longitudinal section mounted on the inclined face of the fixed section and having lateral adjustment on the inclined face of said section. 70

2. In a feeding mechanism of the type described, the combination of a work holding hopper and its vertically moving selector slide, the upper edge of which has an inclined formation, of an inclined runway, comprising a fixed longitudinal section formed with an inclined upper face and a longitudinal section mounted on the inclined face of the fixed section and having lateral adjustment on the inclined face of said section. 85

3. In a feeding mechanism of the type described, the combination of a work holding hopper and its vertically moving selector slide, of an inclined runway, comprising a fixed longitudinal section formed with an inclined upper face and a longitudinal section mounted on the inclined face of the fixed section and having lateral adjustment on the inclined face of said section, and an endless carrier mounted on said adjustable section with its upper stretch arranged in the guide channel formed by said sections. 95

4. In a feeding mechanism of the type described, the combination of work holding hopper and its vertically moving selector slide, of an inclined runway, comprising a fixed longitudinal section formed with an inclined upper face and a longitudinal section mounted on the inclined face of the fixed section and having lateral adjustment on the inclined face of said section, an endless carrier mounted on said adjustable section with its upper stretch arranged in the guide channel formed by said sections, and means for driving said endless carrier, the same comprising a sectional shaft and extensible coupling arranged between a power shaft and a carrying sheave of said carrier. 105

5. In a feeding mechanism of the type described, the combination of a work holding hopper and its vertically moving selector slide, of an inclined runway, comprising a fixed longitudinal section formed with an inclined upper face and a longitudinal section mounted on the inclined face of the fixed section and having lateral adjustment on the inclined face of said section, and a rider rail arranged longitudinally above the guide channel formed by said sections. 115

6. In a feeding mechanism of the type de-
scribed, the combination of a work holding
hopper and its vertically moving selector
slide, the upper edge of which has an in-
5 clined formation, of an inclined runway,
comprising a fixed longitudinal section
formed with an inclined upper face and a
longitudinal section mounted on the inclined
face of the fixed section and having lateral
10 adjustment on the inclined face of said sec-
tion, and a rider rail arranged longitudinally
above the guide channel formed by said
sections.

In testimony whereof I hereunto affix my
15 signature.

ROBERT C. DANLY.
